Primary Examiner — T. Chase Nelson*Assistant Examiner* — Mark Cavanna(74) *Attorney, Agent, or Firm* — Barnes & Thornburg LLP**(57) CLAIM**

The ornamental design for a head support pad for surgery, as shown and described.

DESCRIPTION

FIG. 1 is a perspective view of a head support pad for surgery in accordance with a first embodiment showing my new design;

FIG. 2 is a top plan view thereof;

FIG. 3 is a side elevation view of the right side thereof;

FIG. 4 is a perspective view of a head support pad for surgery in accordance with a second embodiment of my new design;

FIG. 5 is a top plan view thereof; and,

FIG. 6 is a side elevation view of the right side thereof.

The broken lines are included for the purpose of illustrating portions of the head support pad for surgery that form no part of the claimed design.
